(57) **CLAIM**

The ornamental design for a knee ice pack, as shown and described.

DESCRIPTION

FIG. 1 is a front left perspective view of a knee ice pack that is in a formed position as it would be if it were implemented on a user's knee.

FIG. 2 is a front view of a knee ice pack that is in a formed position as it would be if it were implemented on a user's knee.

FIG. 3 is a back view of a knee ice pack that is in a formed position as it would be if it were implemented on a user's knee.

FIG. 4 is a right-side view of a knee ice pack that is in a formed position as it would be if it were implemented on a user's knee.

FIG. 5 is a left-side view of a knee ice pack that is in a formed position as it would be if it were implemented on a user's knee.

FIG. 6 is a top view of a knee ice pack that is in a formed position as it would be if it were implemented on a user's knee.

FIG. 7 is a bottom view of a knee ice pack that is in a formed position as it would be if it were implemented on a user's knee.

FIG. 8 is a front right perspective view of a knee ice pack that is in a flat position.

FIG. 9 is a front view of a knee ice pack that is in a flat position.

FIG. 10 is a back view of a knee ice pack that is in a flat position.

FIG. 11 is a right-side view of a knee ice pack that is in a flat position.

FIG. 12 is a left-side view of a knee ice pack that is in a flat position.

FIG. 13 is a top view of a knee ice pack that is in a flat position; and,

FIG. 14 is a bottom view of a knee ice pack that is in a flat position.

The broken lines depict portions of the knee ice pack that form no part of the claimed design.
